Victor Doriot:

UNITED STATES PATENT OFFICE.

VICTOR DORIOT, OF BRISTOL, TENNESSEE, ASSIGNOR OF ONE-HALF TO
WILLIAM WALLACE, OF SAME PLACE.

SAFETY ATTACHMENT FOR BOTTLES, &c.

SPECIFICATION forming part of Letters Patent No. 358,434, dated March 1, 1887.

Application filed December 14, 1885. Serial No. 185,630. (No model.)

To all whom it may concern:

Be it known that I, VICTOR DORIOT, a citizen of the United States, residing at Bristol, in the county of Sullivan and State of Tennessee, have invented a new and useful Improvement in Safety Attachments for Bottles, &c., of which the following is a specification, reference being had to the accompanying drawings.

10 This invention relates to safety attachments for bottles, &c., and is especially adapted to that class of bottles which are to contain poisonous substances; and the invention has for its object to provide a simple and convenient attachment susceptible of adjustment to different-sized bottles, and which will be adapted to sound an alarm when the stopper of the bottle is withdrawn, and thus notify the party handling the bottle that it contains poison.

20 With this object in view the said invention consists in the peculiar construction and combinations of parts, as will be hereinafter set forth, and particularly pointed out in the claims.

25 In the accompanying drawings, Figure 1 is a perspective view of that particular class of bottles used by pharmacists to contain their medicines, showing my improved safety attachment fitted to the neck of the bottle. Fig. 2 is a longitudinal section of the upper portion of the bottle. Fig. 3 is a horizontal section on the line $x-x$, Fig. 2. Fig. 4 is a side elevation showing the attachment applied to another form of bottle. Fig. 5 is a plan view 35 of the stopper illustrating the arrangement of the bend on the operating-rod.

Like letters are used to indicate corresponding parts in the several figures.

Referring to the drawings, A designates a 40 bottle of the class before mentioned, having my improved attachment fitted to the neck thereof.

45 My attachment comprises, essentially, a band to encircle the neck of the bottle, a bell or gong, a hammer or striker, and an operating-rod connected to the hammer and fitting over the stopper of the bottle, so that the stopper cannot be withdrawn without operating the hammer or striker to sound the alarm.

50 The band B comprises two semicircular sec-

tions, a a', hinged or pivoted together at one end, the section a having its other end turned outward or formed with a projecting lug which is slotted at b, and the section a' carrying a screw-threaded bar C, which is hinged to the 55 section. In adjusting the band to the neck of the bottle the inner surface of each section is padded with leather or other soft material, as at d, and since the sections are hinged together they are allowed to be extended or 60 swung laterally in clasping the neck of the bottle. When they have been adjusted in position the threaded bar C is passed through the slot b in the lug of the adjacent section, a, and a thumb-screw, D, worked over the bar 65 against the lug to hold the two sections of the band together and retain the band in position on the neck of the bottle.

The thumb-screw D should be tightened sufficiently to retain the band rigidly on the 70 bottle, and to prevent undue strain on the neck thereof, and also avoid scratching, the band is padded, as before stated. This band B may be adjusted to different-sized bottles within a certain limit. The construction of this band 75 may be changed at will to suit the various circumstances of its application.

Any suitable hinge or pivotal connection between the sections of the band may be employed, the essential feature being merely to 80 provide two hinged sections having an adjustable connection to allow the separation of the sections to clasp the neck of the bottle and their subsequent connection together to hold the band in place. A post or stud, E, projects outwardly from one of the sections of the band B, said post having its outer end threaded to receive a thumb-screw, G. The bell or gong H, which is preferably elliptical in form, with its concave side facing the bottle, is provided with a central opening to allow the passage of the screw-threaded portion of the post or stud E, the thumb-screw G screwing over 90 the threaded end of the post and binding against the bell to hold it thereon.

95 The section a' of the band B is provided with outwardly-extending ears e at its upper and lower edges, said ears being perforated for the passage of the vertical operating-rod I, the upper end of which is bent inwardly at right 100

angles over the stopper of the bottle, so as to rest on the stopper when the latter is closed down and provide a contact-point, *m*, and thus the withdrawal of the stopper serves to actuate 5 the operating-rod, for the purpose hereinafter more fully explained. Located on the rod *I*, between the ears *e*, is a sleeve, *J*, provided with an enlargement, *f*. A coiled spring, *K*, is wound around the plain portion of the sleeve 10 *J*, and has one end thereof bearing against the band *B* and the other end secured in the enlargement *f* of the sleeve. A set-screw, *g*, passes through the enlargement *f*, so as to hold the sleeve rigidly on the rod *I*.

15 To the enlargement *f* of the sleeve is secured one end of a horizontal arm, *L*, which carries at its free end a ball or enlargement, forming a hammer or striker, *F*, which is adapted to act against the bell. In practice the stud or 20 post *E*, which supports the bell or gong, is placed in such relative position to the other parts that the said bell will entirely inclose the hammer, its operating-rod, and the spring-connection, and thereby conceal and protect 25 the parts.

30 In operation the spring *G* serves to keep the hammer normally extended, but not touching the inner surface of the bell, being held away therefrom by the end of the striker-arm *L* engaging with the post *E*, so that when the rod *I* is partially rotated by the striking of the stopper against the bent upper end or contact-point *m* the spring will be wound or compressed and the hammer or striker withdrawn away 35 from the bell. When the stopper has passed the rod *I* the spring exerts its power and returns the hammer or striker to its normal position against the bell, causing it to strike the latter with sufficient force to sound an alarm.

40 The bend on the upper end of the operating-rod rests normally over the stopper, so that the latter cannot possibly be withdrawn without operating the rod to sound an alarm. The spring normally retains the operating-rod in 45 this position, and thus when the stopper has acted upon the bend on the upper end of the rod to force said rod outward and has passed the rod the spring will return the bend on the rod to its normal position. When inserting 50 the stopper the latter will also strike the bend *m* on the rod to sound the alarm, as before explained. Thus both in withdrawing and replacing the stopper the bell will be sounded, so that should the first alarm be unnoticed the 55 last one will doubtless have the desired effect and stay the reckless hand of the user.

It is well known that when a druggist is suddenly awakened at night by a call at the bell his more or less drowsy condition makes it

possible, when attending to the call, for mis- 60 takes to occur through carelessness or inattention. My device is adapted to recall him to his senses by notifying him when he removes the stopper that the bottle he is handling contains poison, and thus cause him to act with 65 caution in his subsequent movements.

By placing one of my attachments on each of the bottles containing poisonous substances, even those who are unacquainted with the properties of medicine will know at a glance that the 70 bottle contains poison, and be caused to act accordingly. They cannot plead ignorance of the nature of the contents of the bottles, since the mere fact of a bell being placed on the bottle will be sufficient to raise the question 75 as to the reason of the peculiar distinction. Having once become aware of the reason, whenever the bell sounds in opening or closing the stopper of the bottle, the pharmacist will be warned to proceed carefully in apportioning 80 the amount desired for use. The carelessness and inattention of the trade will be thus guarded against, and the purchaser will feel assured of his safety when dealing with those having my attachments applied to their bottles containing 85 poison.

I do not wish to be limited to mere details of construction, as such may be changed at will without departing from the spirit of my invention.

90 I am aware that it is old to provide a bell-alarm for bottles, to be sounded only upon the withdrawal of the stopper. My attachment is held in the path of the stopper at all times, so as to be operated both by the withdrawal 95 and insertion of the stopper.

Having described my invention, what I wish to claim is—

1. A bottle and its stopper, in combination with a bell and bell hammer and a lever held 100 in the path of the stopper at all times, so as to sound the alarm both upon the withdrawal and insertion of the stopper, as set forth.

2. The herein-described attachment for bottles and other receptacles having stoppers, 105 the same comprising an adjustable band to connect with the bottle, the bell or gong, the spring-actuated hammer or striker, and the operating-rod connecting with the hammer or striker, and held in the path of movement of 110 the stopper, as set forth.

In testimony that I claim the foregoing as my own I have hereto affixed my signature in presence of two witnesses.

VICTOR DORIOT.
